DESIGN FOR A PILE FABRIC OR SIMILAR ARTICLE

Juanita G. Todd, Yonkers, N. Y., assignor to Sidney Blumenthal & Co., Inc., New York, N. Y., a corporation of New York

Application November 22, 1938, Serial No. 81,286

Term of patent 3½ years

To all whom it may concern:

Be it known that I, Juanita G. Todd, a citizen of the United States and a resident of Yonkers, in the county of Westchester and State of New York, have invented a new, original, and ornamental Design for a Pile Fabric or Similar Article, of which the following is a specification, reference being had to the accompanying drawing, forming a part thereof.

Fig. 1 is a face view of a pile fabric or similar article showing my new design; and

Fig. 2 is a detail section taken in the plane of the line II—II of Fig. 1, looking in the direction of the arrows.

I claim:

The ornamental design for a pile fabric or similar article, substantially as shown.

JUANITA G. TODD.
